UNITED STATES PATENT OFFICE.

VALENTIN JAKOB ODHNER, OF STOCKHOLM, SWEDEN.

LOCKING DEVICE IN CALCULATING-MACHINES.

1,392,847.

Specification of Letters Patent.

Patented Oct. 4, 1921.

Application filed June 11, 1919. Serial No. 303,413.

To all whom it may concern:

Be it known that I, VALENTIN JAKOB ODHNER, a subject of the King of Sweden, and resident of Karlplan 2, Stockholm, in the Kingdom of Sweden, have invented certain new and useful Improvements in Locking Devices in Calculating Machines, of which the following is a specification, reference being had therein to the accompanying drawing.

In calculating machines it is of importance that the different parts, serving for the performance of the calculating operations, are prevented from operating, if any of the parts is in a wrong position, as, otherwise some part or parts may be broken and mis-calculating take place. This invention relates to a device in calculating machines, provided with calculating wheels and with a carriage, in which registering wheels and indicating disks are provided together with a shaft adapted to return the registering wheels and indicating disks to zero, which device prevents the performance of the calculating operation, if the said shaft is in wrong position.

Figure 1 in the accompanying drawing shows in an end view so much of the calculating machine, as is necessary to illustrate the invention. Figs. 2 and 3 show the parts belonging to the invention in top views and in different positions. Fig. 4 shows in a top view a modified form of the invention.

1 is the shaft, carrying the calculating wheels 2, and 3 is the shaft rotatably and slidably mounted in the carriage 4 and carrying the registering wheels and the indicating disks. The shaft 1 is rotated, as usually, by a crank, manually operated and a gearing. The shaft 3 is provided with ordinary wings 4' or the like for the rotating of the same. As the shaft is rotated a projection 5 provided on the same slides on an oblique stationary surface 6 on the carriage, so that the shaft is moved longitudinally for a distance, during which movement pins on the shaft are brought into engagement with pins provided on the registering wheels and return the said wheels and the indicating disks to zero. After the rotation through one revolution the shaft 3 is removed longitudinally to its original position by a spring 7.

On a pin or shaft 8 a disk 9 is rotatably mounted. A toothed wheel 10 is fixed to or made integral with the said disk and meshes with a toothed wheel 11 on the shaft 1. In

the drawing the said toothed wheels 10, 11 have the same number of teeth, so that the disk 9 is rotated through one revolution during each revolution of the shaft 1. In the edge of the disk 9 a notch 12 is provided. A bar 13 is located in guides provided in the carriage 4 and slideable longitudinally of the same, the said bar extending through the notch 12 of the disk 9 and provided with notches 14 in such positions, that, as the carriage is moved into its different positions, while the shaft 3 is in its normal position, one of the said notches 14 is located opposite to the disk 9, as shown in Fig. 2. On the carriage a two-armed lever 15 is swingably mounted, which by means of a slot and pin joint 16 is connected with the bar 13 and by means of a fork 17 engages a circular flange 18 on the shaft 3.

The described device operates in the following manner. As the shaft 3 is in its normal position, Fig. 2, and the carriage 4 is properly adjusted, one of the notches 14 of the bar 13 is opposite to the disk 9. Consequently, the latter may be rotated without being prevented by the bar 13 and also permits the calculating wheels to be rotated. As the shaft 3 is rotated and is moved longitudinally for returning the registering wheels and indicating disks to zero, the shaft 3 by means of the flange 18 and the lever 15 moves the bar 13 longitudinally, so that one of its solid parts enters the notch 12 of the disk 9, as shown in Fig. 3. If the shaft 3 is rotated through a whole revolution or to its starting position, it is pushed backward by the spring 7 and consequently returns the bar 13 into its normal position with one of its notches 14 located opposite to the disk 9. If on the other hand the shaft 3 is not rotated through a whole revolution and consequently the registering wheels and the indicating disks are not returned to zero, one of the solid parts of the bar 3 remains in the notch 12 of the disk 9, as shown in Fig. 3, so that the bar prevents the disk 9 and the calculating wheels from being rotated. If the carriage 4 is not shifted into one of its proper positions, the bar 13, which is moved together with the carriage, will be located in such position, that one of its solid parts is located in the notch 12 of the disk 9, so that also in this case the calculating wheels are locked.

If on the other hand, the calculating wheels are not rotated through a whole revo-

lution, *i. e.*, the crank mentioned above has not been returned into its normal position, a solid part of the edge of the disk 9 will be located in one of the notches 14 of the 5 bar 13 and prevents the shaft 3 from being rotated and the carriage 4 from being moved.

Consequently, the described device insures, that the calculating wheels as well as 10 the shaft 3 always must be returned into their normal positions respectively and that the carriage always must be adjusted in proper position, in order that the machine may operate.

15 The form of the invention shown in Fig. 4 differs from that described above only by the bar 13 by means of an arm 18 being rigidly connected with a sleeve 19, inclosing the shaft 3 and partaking in its longitudinal motion.

Having now described my invention, what I claim as new and desire to secure by Letters Patent is:

1. In a calculating machine the combination 25 with calculating wheels, a carriage, registering wheels provided in the said carriage and a rotatable axially movable shaft for returning the said registering wheels to zero, of a catching device and 30 means connecting the said device with the said shaft in such manner that its functioning is dependent on axial movement of the shaft the said catching device locking the calculating wheels, when the carriage is in 35 proper position and the said shaft is in wrong position and locking the said shaft when the calculating wheels are in wrong position.

2. In a calculating machine the combination 40 with the calculating wheels, a carriage, registering wheels provided in the said carriage, a rotatable shaft for returning the said registering wheels to zero, which shaft is slidable longitudinally, a preferably circular disk, rotating with the said calculating 45 wheels, a notch provided in the edge of the said disk, a bar, provided in the said carriage and extending longitudinally of the same, said bar coöperating with the

notch of the said disk, notches provided in 50 the said bar and corresponding to different positions of the said carriage, of means supporting the said bar in a slidable manner and means connecting the bar with the said shaft, so that it is moved longitudinally as 55 the shaft is moved longitudinally, substantially as described and for the purpose set forth.

3: In a calculating machine the combination with the calculating wheels, a carriage, 60 registering wheels provided in the said carriage, a rotatable shaft for returning the said registering wheels to zero, which shaft is slidable longitudinally, a preferably circular disk, rotating with the said calculating 65 wheels, a notch provided in the said disk, a bar, provided in the said carriage and extending longitudinally of the same, the said bar coöperating with the notch of the said disk, notches provided in the said bar and 70 corresponding to different positions of the said carriage, of means supporting the said bar in a slidable manner, a flange on the said shaft and a two-armed lever connecting the 75 said bar with the said flange.

4. In a calculating machine, a movable carriage, an axially movable shaft carried by the carriage, a spring for moving said shaft in one direction, a cam device for moving the shaft in the opposite direction, a disk carried 80 by said cam device, a second shaft carrying a wheel provided with a peripheral notch, a sliding bar coöperating with said wheel, adapted to engage said notch for preventing rotation of said wheel, and provided 85 with a notch designed to register with the wheel to permit its rotation, and a connection between said disk and said bar, whereby rotation of said cam device will cause said bar to lock the wheel against rotation, 90 and whereby the wheel when in register with the notch of the bar will prevent movement of the bar and rotation of the cam device.

In witness whereof, I have hereunto 95 signed my name.

VALENTIN JAKOB ODHNER.
